UNITED STATES PATENT OFFICE.

WILLIAM L. CANNIFF, OF JANEVILLE, WISCONSIN, ASSIGNOR TO GENERAL MOTORS CORPORATION, OF DETROIT, MICHIGAN, A CORPORATION OF DELAWARE.

TRACTOR-HITCH.

1,396,927.

Specification of Letters Patent. Patented Nov. 15, 1921.

Application filed May 3, 1919. Serial No. 294,472.

To all whom it may concern:

Be it known that I, WILLIAM L. CANNIFF, a citizen of the United States, and resident of Janesville, Rock county, State of Wisconsin, have invented certain new and useful improvements in Tractor-Hitches, of which the following is a specification.

My invention relates to draft devices for use with plows which are to be drawn by traction engines or tractors, and the object thereof is to provide a draft device having features of construction whereby it may be used with plows having various numbers of individual plow elements or plow bottoms; so that draft devices all of one standard type and size, and identical in all respects one with another, may be applied to and used to draw two bottom, three bottom or four bottom plows.

Heretofore plows having different numbers or separate plows or bottoms have been equipped with draft devices differing one from another, and each capable of use only with the particular size of plow for which it was designed; even though such devices may have been all of one general type and made up of elements differing one from another only in detail. Such a practice, as will be appreciated, has necessitated the manufacture and storage of draft devices differing but little one from another, as a sufficient supply of the particular forms thereof adapted for use with each size of plow manufactured had to be kept in stock; and has prevented the standardization of the draft devices and the securing of the advantages incident to the manufacture and use of a standard product.

My invention contemplates a draft device having features of construction whereby it may be used to draw plows of such different sizes as are commonly made and used, thus providing a single standard device capable of use with different sizes of plows or plows having different numbers of plow bottoms. Of course the strains to which the device is subjected when in use are greater in the case of the larger than in the case of the smaller plows; but the structural material which will as a matter of practical necessity be used in order to provide sufficient rigidity to resist bending or other injury to the device when in use, will provide a device having sufficient strength for use with the

larger sizes of plows with which it is designed to be used.

In the drawing accompanying and forming a part of this specification and wherein the preferred embodiment of my invention is illustrated, although it will be appreciated that the same may be embodied in various other forms all within the scope of the concluding claims:

Figure 1 is a view showing my invention as applied to a four bottom plow;

Fig. 2 is a view showing the same as used with a three bottom plow;

Fig. 3 is a view showing my invention upon a larger scale, and as applied to a plow having two bottoms or individual plows;

Fig. 4 is a view showing a detail; and,

Figs. 5 and 6 are views showing two of the various positions which the parts of my improved draft device may be made to assume in adjusting the same.

In the drawing, the reference numeral 10 designates a draw bar the forward end of which is connected with a tractor shown conventionally in Fig. 2 through any suitable connecting member 11, and the rear end of which is pivotally connected with a cross bar 12 adjacent one end thereof, and which cross bar in turn is connected with the forward ends of the beams of the plows which are drawn by the tractor and through which cross bar the pull of the tractor is communicated to the plows.

The reference numeral 13 designates an adjusting bar the rear end of which is also pivotally connected with the cross bar 12 adjacent the other end thereof, and the forward end of which is pivotally connected with a link 14 and which link is pivotally connected with the draw bar 10 at 15; said link being provided with an adjusting member shown as in the form of a curved segment 16 formed integrally therewith, and having a plurality of holes spaced apart one from another, as best shown in Fig. 3.

The segment 16 is confined by a clip 17 secured to the draw bar 10, see Fig. 4; and a pin 18 may be passed through holes in the clip and draw bar 10, and through one or another of the holes in the segment 16 whereby the relation of the parts may be changed and said parts made to assume the positions shown in Figs. 5 and 6, as well as other positions.

The purpose of the adjustment thus provided for is to vary the angle or direction of the line of pull or tractive effort exerted upon the cross bar through the draw bar 10 and the adjusting bar 13, and cause the plows to draw properly, and cut furrows of the proper width; it being appreciated that while the bar 10 is referred to as the draw bar the pull upon the cross bar 12 is in fact transmitted thereto through both the said cross bar and the adjusting bar 13, and that the feature of adjustability of the two bars in question provided for as above pointed out is quite independent of the number of 15 separate plows or bottoms being pulled by the tractor; the purpose of the elements, whereby adjustment is provided for being to cause the plow as a whole to follow the tractor properly, and to turn furrows of the 20 proper width, irrespective of the number of separate plows or bottoms being pulled at any given time.

In order to adapt the draft mechanism made up of elements above enumerated to 25 plows having different numbers of individual plows or bottoms, so that two bottom, three bottom or four bottom plows may be equipped with draft devices all of one standard size and construction, the cross bar 12 is provided 30 with series of holes adjacent each of its ends; which holes permit the points of attachment of the rear ends of the bars 10, 13, to the cross bar, as well also as the points of connection between the cross bar and the 35 beam clevis which in turn is connected with the beams of the plows to be pulled, to be varied in the different sizes of plows.

The construction above explained and the 40 capability of variation incident thereto above pointed out enables the line of pull along which tractive force is exerted on the plow to be positioned approximately centrally thereof, irrespective of the number of separate plow bottoms with which the plow is 45 equipped.

The fine adjustment which is desirable in 50 order to cause a particular plow to follow a tractor properly, and the individual plows thereof to cut furrows of the proper width, is provided for by the swinging link 14 and the perforated segment 16; although it will be appreciated that the range of adjustment secured by these members would not be sufficient in cases of plows having different 55 numbers of bottoms to secure the proper following of the plows, if the connection between the cross bar and the forward ends of the plow beams was of a fixed and invariable character, and one which could not be 60 changed in order to adapt the draft device to the number of plow bottoms present in particular plows.

In order, therefore, to provide for the more 65 extensive range of variation or adjustment necessary to enable a single draft device or

draft devices all of one standard form and of like size to be used with plows having different numbers of plow bottoms, series of holes are provided adjacent the two ends of the cross bar; whereby the points of connection 70 between the rear ends of the bars 10, 13 and the cross bar, and between the cross bar and the plow, may be varied within comparatively wide limits.

Thus in Fig. 1 the beam clevis 20 through 75 which the front ends of the beams 21 of the four individual plows therein shown are connected with the cross bar 12, is itself connected with said cross bar by bolts extending through the right-hand end holes of 80 the series of holes at the two ends of the cross bar; while the connections between the rear ends of the bars 10, 13 and the said cross bar are made by bolts passing through the left-hand end holes of the two series, thus bringing 85 the line of pull along which the tractive force of the tractor is exerted between the two inner plows of the series.

In Fig. 2 the connections between the cross bar 12 and the beam clevis 22 at the forward 90 ends of the three separate plows therein illustrated are unchanged, but the rear ends of the bars 10, 13 are connected with the cross bar by bolts passing through the middle holes of the two series of holes, thus bringing the 95 line of pull close to but somewhat to the left of the beam 23 of the middle plow of the series; while in Fig. 3 the clevis 24 is connected with the cross bar by bolts passing through the left-hand holes of the two series 100 of holes, and the rear ends of the bars 10, 13 by bolts extending through the middle holes of the two series, the line of pull being between the beams 25 of the two plows there 105 shown and closest to the left-hand one of said plows.

It will be appreciated that the two series of holes at the ends of the cross bar 12 may have more than three holes in each, should a larger number be found necessary in order 110 to adapt the draft device to the various sizes or types of plows manufactured in any particular manufacturing establishment. It will also be appreciated that while the construction of my improved draft device is 115 such that draft devices of standard construction and identical one with another may be applied to two bottom, three bottom, four bottom and other sizes or types of plow, it is not contemplated that the connections between the plow clevis and the cross bar, or between the bars 10, 13 and the cross bar, will be disturbed after said connections have been 120 determined upon and properly made by the manufacturer; such adjustment as the user may find it desirable to make being provided for by the bar 13, link 14, and curved segment 16, as hereinbefore explained.

The drawing illustrates and the foregoing specification describes in detail the pre- 125

ferred embodiment of my invention. It will be appreciated, however, that minor changes may be made in the device disclosed, and the mechanical details thereof varied, without departing from my invention; and that my invention includes all such variations and modifications of the specific form thereof herein disclosed as come within the scope of the concluding claims wherein the features wherein my invention consists are particularly pointed out.

Having thus described and explained my invention, I claim and desire to secure by Letters Patent:

1. In a draft device of the class described, a cross bar; a draft bar the rear end of which is pivotally connected with said cross bar adjacent one end thereof; an adjusting bar the rear end of which is pivotally connected with said cross bar adjacent the other end thereof; a link pivotally connected with said draft bar and with which link the forward end of said adjusting bar is pivotally connected; a curved adjusting segment formed integrally with said link and having a series of spaced holes each of which may be made to register with a hole in said draft bar; and two series of holes in said cross bar and located one series adjacent each end thereof.

2. In a draft device of the class described, a cross bar; a draft bar the rear end of which is pivotally connected with said cross bar adjacent one end thereof; an adjusting bar the rear end of which is pivotally connected with said cross bar adjacent the other end thereof; a link pivotally connected with said draft bar and with which link the forward end of said adjusting bar is pivotally connected; an adjusting member connected with said link and having a series of spaced holes each of which may be made to register with a hole in said draft bar; and two series of holes in said cross bar and located one series adjacent each end thereof.

3. In a draft device of the class described, a cross bar; a draft bar the rear end of which is pivotally connected with said cross bar adjacent one end thereof; an adjusting bar the rear end of which is pivotally connected with said cross bar adjacent the other end thereof; a link pivotally connected with said draft bar and with which link the forward end of said adjusting bar is pivotally

connected; and a curved adjusting segment 55 formed integrally with said link and having a series of spaced holes each of which may be made to register with a hole in said draft bar.

4. In a draft device of the class described, a cross bar; a draft bar the rear end of 60 which is pivotally connected with said cross bar adjacent one end thereof; an adjusting bar the rear end of which is pivotally connected with said cross bar adjacent the other end thereof; a link pivotally connected with 65 said draft bar and with which link the forward end of said adjusting bar is pivotally connected; and an adjusting member connected with said link and having a series of spaced holes each of which may be made to 70 register with a hole in said draft bar.

5. In a draft device of the class described, a draft bar the rear end of which is adapted to be pivotally connected with a cross bar; 75 an adjusting bar the rear end of which is adapted to be pivotally connected with said cross bar at a point spaced apart from the pivotal connection between the draft bar and cross bar; a link pivotally connected with said draft bar and the free end of 80 which is pivotally connected with the forward end of said adjusting bar; an adjusting member connected with said link; and means for securing said adjusting member to said draft bar in a plurality of positions, 85 to thereby adjust the position of said adjusting member.

6. In a draft device of the class described, a draft bar the rear end of which is adapted to be pivotally connected with a cross bar; 90 an adjusting bar the rear end of which is adapted to be pivotally connected with said cross bar at a point spaced apart from the pivotal connection between the draft bar and cross bar; a link pivotally connected with 95 said draft bar and the free end of which is pivotally connected with the forward end of said adjusting bar; a curved adjusting segment connected with said link at or adjacent the pivotal connection between the forward 100 end of said adjusting bar and said link; and means for securing said adjusting segment and said draft bar together in a plurality of positions to thereby adjust the position of said link.

In testimony whereof I affix my signature.

WILLIAM L. CANNIFF.
